A. R. CLAS

WINDOW CONTROL MECHANISM

Filed Sept. 24, 1923

UNITED STATES PATENT OFFICE.

ANGELO ROBERT CLAS, OF TOLEDO, OHIO.

WINDOW-CONTROL MECHANISM.

Application filed September 24, 1923. Serial No. 684,352.

To all whom it may concern:

Be it known that I, ANGELO ROBERT CLAS, a citizen of the United States, and a resident of Toledo, in the county of Lucas and State of Ohio, have invented a new and useful Window-Control Mechanism, which invention is fully set forth in the following specification.

This invention relates to window control mechanisms and particularly to those used in connection with the windows of automobiles.

The object of the invention is the provision of a novel mechanism of the class described which is simple and inexpensive in its construction, composed of few parts and capable of being easily attached as a unit to a window frame.

The invention is fully described in the following specification, and while in its broader aspect it is capable of embodiment in numerous forms, two embodiments only thereof are illustrated in the accompanying drawings, in which,

Fig. 1 is a fragmentary outer side elevation of a window frame and associated window, with the latter in partly lowered position, and with a mechanism embodying the invention associated therewith, parts of the frame and control mechanism being in section. Fig. 2 is a similar view of a slightly modified form of the invention, and Figs. 3 and 4 are enlarged sections on the lines 3—3 and 4—4, respectively, in Figs. 1 and 2.

Referring to the drawings, 1 designates a window frame forming the window opening 2 in its upper portion and a chamber 3 in its lower portion into which latter the glass or other window member 4 may be lowered from closing relation to the opening, as is customary in the windows of automobiles and the like.

At the upper inner side of the chamber 3 is located the customary lock-board 5, which extends crosswise of the inner frame from side to side thereof. A bracket plate 6 is screwed or otherwise suitably secured to the inner side of the lock-board 5 near one end thereof, with its lower end, in the present instance, projecting a short distance below the lock-board.

An arm 7 is pivoted to the lower extended end of the plate 6 for vertical rocking movements at the inner side of the lock-board 5 in parallel relation thereto and has its outer

end extending toward the center of the lock-board and provided with a roller 8 disposed in the path of vertical movements of the window member 4 and on which the lower edge of such member rests. The opposite end of the arm 7 projects a short distance from its pivot and is connected by a spring 9 to a convenient part of the frame to serve as a means for counterbalancing the weight of the window member on the arm 7, as well understood in the art.

An operating lever 10 is fulcrumed to the plate 6 a distance above the arm 7 and has one arm extending from its pivot in the general direction of projection of the arm 7 and connected by a link 11 to said arm, whereby the arm 7 and lever are caused to have rocking movements in unison. The other arm of the lever projects towards the adjacent side of the frame 1 and has pin 75 and slot connection 12 with a member 13, which projects rigidly inward from a carrying rod 14 toward the pivot of the lever. The rod 14 depends from a slide block 15, which is mounted for vertical sliding movements in a guide member 16 mounted in a channel 17 provided in the adjacent side or upright member of the frame 1, and at the inner side of the guide provided in said frame upright for the window member 4. The slide block 15 carries a detent 18, which is mounted for limited reciprocatory movements therein transversely of the guides 16 and is adapted to project into any one of a set of notches 19 provided in the inner wall of the guide member 16 and with which the detent may register. A spring 20 normally holds the detent in engagement with a registering notch 19, and a control handle 21 is mounted in accessible position on a stem of the detent, which projects through the slide block 15, and without the guide 16 through a longitudinally extending slot 22 therein.

It is evident with this arrangement that any vertical movement of the slide block 15 within the guide 16 imparts a rocking movement to the lever 10 and through the link 11 to the rocker arm 7 and either effects a raising of the window member 4 or permits lowering of the same, depending on the direction of movement of the slide block. This forms a very simple and inexpensive window control mechanism of the type in which movement is communicated to the

window member from a reciprocatory movement of a vertically movable control member at the side of the window.

In the modified form of the invention shown in Figs. 2 and 4 a rack bar and pinion connection between the operating rod 14 and lever 10 is substituted for the link and pin and slot connection above described. In this modified form of the invention the lower end of the guide for the slide block 15 (not shown) which guide is designated 16^a is extended down into the chamber 3 to form a guide having a vertically reciprocatory rack bar 25 attached to the lower end of the rod 14, and such rack bar engages the teeth of a segmental pinion 10^a provided on the adjacent arm of the lever 10, the teeth of the rack bar and pinion engaging through the longitudinal slot 22 in the exposed side of the guide.

It is evident that in either form of the invention, a shifting of the control handle 21 vertically at a side of the window member communicates a rocking movement to the lever 10 and from it to the arm 7 to effect a raising or lowering of the window member.

I wish it understood that my invention is not limited to any specific construction, arrangement or form of the parts, as it is capable of numerous modifications and changes without departing from the spirit of the claims.

Having thus described my invention, what I claim as new and desire to secure by Letters Patent, is,—

1. The combination with a slidable window member, of a frame guiding the movements of the member, an arm pivotally carried by the frame for vertical rocking movements and supporting the window, counterbalancing means for the arm, a lever fulcrumed to the frame, means connecting the lever and arm for imparting rocking movements from one to the other, and manually operable control means guided for vertical reciprocatory movements in a side of the window frame parallel to the movement of the window, and connected to the lever to cause a rocking thereof when the control means is moved.

2. The combination with a slidable window member, of a frame having a chamber

receiving said member in its open position, an arm mounted for vertical rocking movements within the chamber and having supporting engagement with the window member, a counterbalancing means for the arm, a lever mounted within the member for vertical rocking movements and having an arm projecting in the general direction of projection of said first arm, connection between said lever arm and the window supporting arm to cause them to have rocking movements in unison, a vertical guide in the side upright member of the frame, a slide block mounted for vertical reciprocatory movements in said guide, control means connected to the slide for operating the same and operable to releasably secure it in adjusted position, a rod depending from the slide, and connection between the rod and lever within the chamber for imparting a rocking movement to the lever from a vertical reciprocatory movement of the rod.

3. The combination with a window frame having a window opening in its upper portion, a window receiving chamber in its lower portion, and a lock-board extending across the upper portion of the chamber at one side thereof, a window member slidably mounted in the frame for lowering movements in the chamber, a plate fixed to the inner side of the lock-board, an arm pivoted to the plate adjacent to the lower edge of the lock-board for vertical rocking movements and having its outer end projecting below the central portion of the lower edge of the window member in supporting engagement therewith, a horizontally disposed lever pivoted to the plate above said arm for vertical rocking movements, a link connecting one arm of the lever to said window supporting arm, a vertical guide in the side of the window frame adjacent to said lever, and means mounted for vertical sliding movements in the guide at a side of the window opening and having operative connection with the lever to impart a rocking movement thereto from a vertical movement of said means.

In testimony whereof I have hereunto subscribed my name to this specification.

ANGELO ROBERT CLAS.
